INSOLE

Charles Tweedie, Jefferson City, Mo., assignor to
 Tweedie Footwear Corporation, Jefferson City,
 Mo., a corporation of Missouri

Application July 5, 1933, Serial No. 679,061

3 Claims. (Cl. 36—22)

My invention relates to the manufacture of shoes. It is especially concerned with the insole. Its principal objects are to simplify the manufacturing operations, provide for the use of less expensive material in the insole and still obtain a better and more flexible shoe, and to obtain other advantages hereinafter appearing. The invention consists principally in the insole and in the method of attaching the upper thereto herein-after described and claimed.

In the accompanying drawing, wherein like reference numerals refer to like parts wherever they occur,

Fig. 1 is a bottom plan view of an insole embodying my invention,

Fig. 2 is a longitudinal section through the forepart of the insole on the line 2—2 in Fig. 1,

Fig. 3 is a transverse section through the shank portion of said insole on the line 3—3 in Fig. 1,
 20 Fig. 4 is a view similar to Fig. 1 showing the upper lasted to the insole,

Fig. 5 is a fragmentary section on the line 5—5 in Fig. 4,

Fig. 6 is a view similar to Fig. 4, showing the 25 shoe as it appears after the removal of the excess lasting allowance of the upper end of the leaves or lips of the lower layer of the insole,

Fig. 7 is a fragmentary cross-section on the line 7—7 in Fig. 6,

Fig. 8 is a fragmentary cross-section on the 30 line 8—8 in Fig. 6,

Fig. 9 is a bottom plan view of the shoe with the outsole secured thereto; and

Figs. 10 and 11 are bottom plan views of in- 35 soles of modified construction.

In the construction illustrated in Fig. 1 the insole comprises a top layer 1 of leather or other suitable material and a lower layer 2 of leather or other suitable material. Both of these layers 40 are of full length except that the front tip of the lower layer is snipped off, as indicated at 3. Between these two layers is a shank stiffener 4, preferably of metal, which is tacked at its front and rear ends to one of the layers, preferably the 45 top layer. The heel portions of the two layers are cemented together the full width thereof, except that the shank stiffener is between them. The portions of said layers forward of the shank are also cemented together except for a broad 50 marginal strip 5 which is left uncemented.

The two layers of the insole are stitched together by lines of stitching 6 on opposite sides of and as close as practicable to the metal shank stiffener. These lines of stitching extend for- 55 wardly substantially parallel with the margins of

the top member continuously to the snipped toe end of the lower layer. The lower layer is slit inwardly from both its side edges just forward of the cemented heel portion thereof, as indicated at 7, and also at points close to the front end of 5 the shank stiffener, as indicated at 8. The free or loose marginal portions 9 of the lower layer, that is, the portions thereof outwardly from the stitching are then bent back along the line of stitching so as to stand out as a leaf or flap at 10 a considerable angle from the top layer.

Preferably, the insole above described is made and handled as a separate article of manufacture. It may, however, be made and embodied in the 15 shoe in a continuous operation. In such case, the top layer 1 may be tacked to a last, the shank stiffener 4 tacked thereon and the lower layer 2 cemented to the top member by any suitable adhesive with the margins of the shank and fore-part of the lower layer left free and bent back at 20 a considerable angle to form the leaf or flap or leaves 9.

Then the upper 10 is pulled over a last and its 25 margins 11 are secured to the leaf or free marginal portion of the lower layer of the insole along the full length thereof on both sides of the shoe, as by staples 12 or other suitable devices. The lasting allowance 13 of the upper is then stitched, cemented or otherwise suitably secured to the 30 marginal portion of the top layer beyond the stitching 6 which secures the lower layer thereto. After the upper is thus secured to the margin of the top layer of the insole (sufficient time being allowed for drying of the cement, if cement is used), the excess material, both of lasting 35 allowance of the upper and of the leaves or lips of the lower layer of the insole, is cut away as closely as practicable to the stitching which holds together the top and lower layers of the insole. The material thus cut away carries with 40 it the staples, stitches or other fastenings used to temporarily hold the edge portion of the lasting allowance of the upper to the leaves or free marginal portions of the lower layer of the insole. Along the shank and heel the lasting allowance 45 is trimmed along a line located between the edge thereof and the fasteners, thereby permitting these fasteners to remain in the shoe. In this condition, the shoe is ready to receive the outsole 14, which may be applied thereto in any usual manner, as by stitching 15, cementing or otherwise. It is noted that the removal of the free leaves or marginal portions of the lower 50 layer of the insole together with the surplus of 55

the lasting allowance of the upper quite close to the stitching 6 makes it entirely practicable to dispense with the filler piece commonly used under the ball of the foot between the inner and outer soles. Such a cut leaves the surface of the lower layer of the insole substantially flush and continuous with the lasting allowance of the upper, with no substantial rib or hollow between them. It is also noted that lasting allowance 10 terminates at the sides of the shank stiffener substantially flush with the ridge formed thereby, thereby providing for greater compactness along the shank of the shoe.

The invention hereinbefore described has a number of important advantages. On account of the metal shank stiffener being pocketed tightly between the upper and lower layers, it can not squeak the way the ordinary shank stiffener sometimes does. The insole, being made of two 15 relatively thin layers, is more flexible than a comparable insole with a single layer; and if still greater flexibility is desired, it is feasible to cut slashes entirely through the lower layer and partway through the top layer without sacrifice of wearing quality. Likewise, it is feasible to effect a considerable saving in cost because the top layer of the insole may be made of thinner material than usual and the lower layer of less expensive material so that the combined cost of 20 the two layers is less than the cost of a comparable insole of a single layer. Likewise, my invention has the advantage that it does not leave in the forepart of the shoe any tacks, staples or fasteners used as temporary aids in the lasting 25 operation, nor does it require any special operation for the removal thereof, because all such devices are, in my process, cut away with the surplus lasting allowance. It is noted also that in 30 comparison with the common practice, my process involves fewer operations.

The insole hereinbefore described admits of modification. Thus, as illustrated in Fig. 11 the lower layer 2a of the insole forward of the shank 45 may, for the sake of economy, be made narrower than the top layer, provided that the leaf or free marginal portion 8a thereof beyond the stitching 6a is sufficiently wide to receive the staples or other fasteners by which the lasting allowance

of the upper is secured thereto in the lasting operation.

Fig. 10 illustrates another modification wherein the metal shank stiffener 16 is tacked to the insole 17 and firmly secured against movement by 5 a second layer 18 secured by lines of stitching 19 as close as practicable thereto along the sides and ends thereof. In this case, the lower layer 18 extends from the back of the heel to a point just 10 forward of the front end of the shank and is 10 firmly cemented to the top layer 17. In such case, the front portion of the insole may be channeled or otherwise adapted for connection to the upper in any known way; or there may be another section of the lower layer conforming to 15 the corresponding portion of the lower layer first described.

What I claim is:

1. An insole comprising a top layer, a lower layer and a shank stiffener interposed between them, said layers being secured together by lines of stitching extending close alongside of said stiffener and substantially parallel with the edge 20 of the top layer at a distance inwardly therefrom, the marginal portion of the lower layer 25 forward of the shank being turned back free from the top layer.

2. An insole comprising a top layer, a lower layer and a shank stiffener interposed between them, said layers being secured by lines of stitching 30 extending close alongside of said stiffener and substantially parallel with the edge of the top layer at a distance inwardly therefrom, said layers being connected together except that the marginal portion of the lower layer forward of the 35 shank is left free to constitute a stitch-receiving flap.

3. An insole comprising a full length top layer, a shorter lower layer cemented thereto and a shank stiffener interposed between them, and 40 substantially coterminous with the shank portion thereof, said lower layer being similar in size and shape to the portion of the top layer from the back end thereof as far forwardly as the tip of the stiffener and said layers being also secured 45 together by lines of stitching extending close alongside of said stiffener.

CHARLES TWEEDIE.
